UNITED STATES PATENT OFFICE.

NORRIS ELMORE CLARK, OF PLAINVILLE, CONNECTICUT.

ART OF METAL-WORKING.

1,165,071.

Specification of Letters Patent. Patented Dec. 21, 1915.

Original application filed May 20, 1908, Serial No. 433,923. Divided and this application filed September 29, 1913. Serial No. 792,247.

To all whom it may concern:

Be it known that I, NORRIS ELMORE CLARK, a citizen of the United States of America, and residing at Plainville, in the county of Hartford and State of Connecticut, have invented new and useful Improvements in the Art of Metal-Working, of which the following is a specification.

My invention relates to improvements in the art of forming expanded metal fabrics.

The main object is to provide a strong fabric which can be manufactured economically. One of the principal uses of such a fabric is as reinforcement for cement, plaster and concrete.

One of my objects is the economical formation of a fabric having longitudinal tension members connected by strands.

The accompanying single sheet of drawings illustrates two forms of products made according to the invention which will be more fully described and claimed herein-after.

Figure 1, is a plan view of a piece of material showing the arrangement of slitting preparatory to expansion. Fig. 2, shows the same stretched or expanded. Fig. 3, shows a modification of slitting. Fig. 4, shows a portion of the stock of Fig. 3 expanded. Fig. 5, is a fragmentary sectional view of a bar and attached strands.

The fabric may be of any width and contain any number of bars, two or more such as 1, 2 and 3. These may be of any cross sectional shape and size. Adjacent bars are integrally connected by a series of members each of which is made up of at least three strands such as 4, 5 and 6. The alternate connectors extend at opposite inclinations, 40 the strands 7, 8 and 9 in the drawing being inclined upward and to the left while strands 4, 5 and 6 are inclined upward and to the right. The connectors 10 and 11 are arranged so as to form the remaining sides 45 of a diamond which is divided across one diameter by the bar 2. The slitting preparatory to expansion is along lines parallel to the bars and in staggered relation, the pairs of slits such as 12 and 13 alternating 50 with slits such as 14 and 15. The bonds between the slits in the row of slits 14 are cut transversely as at 16 and the bonds between the slits in the row of slits 13 are cut transversely as at 17. The slitting between the 55 bars 2 and 3 is symmetrical with the slitting

between bars 1 and 2 so that the product as shown in Fig. 2 is symmetrical about the axis of bar 2. The slitting can be readily effected by automatic cutting mechanism.

The slitting of Fig. 3 omits the bar 2 so that the fabric of Fig. 4 results. Here the connectors form a diamond without any cross bar.

In the drawings I have shown the strands on edge relative to the plane of the fabric. The exact angle is unimportant. The tension bars may also be on edge or inclined as in Fig. 5 if desired.

The slotted stock may be stretched or expanded laterally in any suitable manner. The strands being on edge give greater stiffness to the fabric even when made of light gage stock. The lugs such as 18, 19, 20 and 21 serve as anchors to prevent transverse slipping in concrete when so used.

The method of manufacture is simple and cheap and when properly conducted does not injure the material. It also insures a maximum degree of expansion for the amount of metal employed.

This application is a divisional application from #433,923 filed by me May 20th, 1908, now Patent No. 1,086,027, dated Feb. 3rd, 1914.

What I claim is:—

1. The art of forming a reticulated metal fabric consisting of longitudinally extending unslotted parallel bars and integrally connecting expanded sections, each expanded section consisting of a plurality of rows of integrally connected bent strands, the marginal strands being connected respectively to the adjacent longitudinally extending parallel bars and the intermediate strands being connected respectively to the strands laterally adjacent thereto, which comprises slitting the stock between the parallel bars longitudinally in a plurality of rows parallel to said bars and in staggered arrangement and slitting the stock transversely midway between the ends of the slits in the interior rows and bending the strands and opening the slitted portions.

2. The art of forming a reticulated fabric which consists in slitting a blank to produce longitudinally extending parallel bars and an integrally connecting slotted portion having a plurality of rows of longitudinal slits parallel to said bars and arranged in staggered relation, the metal between the ends

- of the slits in one row being substantially opposite the center of the slits in the adjacent rows and slitted transversely relative to said portions midway between the longitudinal slits forming extensible zigzag strips connecting said bars and then drawing apart the bars to open the slitted portion and form meshwork.
3. The art of forming a reticulated fabric which consists in slitting portions of a sheet to form a blank comprising longitudinally extending parallel bars and an integrally connecting slitted portion having at least four rows of longitudinal slits parallel to said bars, the length of said slits being very materially greater than the distance between said slits and the slits in successive rows being in relatively staggered arrangement and the metal between said bars being slitted transversely relative to said bars so as to form extensible zigzag strips connecting said bars, each strip consisting of at least three strands and drawing apart the bars to extend the strips and form meshwork.
4. The art of forming reticulated metal fabric consisting of longitudinally parallel bars and integrally connecting ties, each tie consisting of at least three strands arranged on edge relative to the plane of the fabric which consists in slitting portions of the metal between the bars longitudinally in a plurality of parallel rows in staggered arrangement and transversely slitting the metal midway between the ends of the slits in the inner rows and drawing apart the bars to open the slitted portions and form meshwork.
5. The art of forming a reticulated fabric which comprises forming a plurality of rows of longitudinal slits between two longitudinal unslotted bars, the slits of alternate rows being transversely opposite each other and the other longitudinal slits overlapping the intervals between the slits of the first mentioned rows, transversely slitting the stock

midway between the ends of said other slits so as to form strands and then separating the unslotted bars, bending the strands and opening the slits.

6. The art of forming a reticulated metal fabric which comprises slitting longitudinal bands of metal between longitudinal unslotted bars and by the slitting, forming four or more rows of parallel longitudinal slits leaving rows of strands connected together by bonds in staggered arrangement, all of the slits being of substantially the same length, the center of each slit lying adjacent the center of the bond between the adjacent slits in the adjacent row of slits, slitting transversely such of the bonds as it is necessary to slit to permit the strands to be bent without stretching the strands materially or buckling the longitudinal unslotted bars, then separating the longitudinal unslotted bars and forming the meshwork.

7. The method of forming a reticulated metal fabric which consists in forming a plurality of bendable strands by making a plurality of rows of longitudinal parallel slits and transverse slits between longitudinal parallel unslotted bars, all of the longitudinal slits being of substantially the same length, the center of each longitudinal slit being along side of a point midway between the ends of the adjacent longitudinal slits in the adjacent row and each transverse slit extending between the central portions of longitudinal slits in alternate rows midway between the adjacent ends of slits in the intervening row of longitudinal slits so as to permit the strands to bend without materially stretching and without buckling the longitudinal unslotted bars, then separating the longitudinal unslotted bars and bending the strands to form the meshwork.

NORRIS ELMORE CLARK.
